UNITED STATES PATENT OFFICE.

WALTER P. MURPHY, OF ST. LOUIS, MISSOURI.

RELEASE-RIGGING.

1,067,052.

Specification of Letters Patent. Patented July 8, 1913.

Application filed September 24, 1909. Serial No. 519,470.

To all whom it may concern:

Be it known that I, WALTER P. MURPHY, a citizen of the United States, and a resident of St. Louis, in the State of Missouri, have 5 invented certain new and useful Improvements in Release-Rigging, of which the following is a specification.

In the drawing, Figure 1 is a top plan view of a car, broken away, with my improved release rigging applied to the end sill; Fig. 2 is a sectional view through the rigging on the line 2--2; and Fig. 3 is an end elevation of the car, broken away, with my rigging applied.

15 1 represents the end sill of a car which may be of any approved type, 2 a coupler of standard type, having the usual locking pin 3.

20 4 are suitable bearings secured to the face of the end sill. These bearings may consist of eye bolts or may be of suitable castings. 5 is the hand operated lever loosely journaled in the bearings 4, the outer end of which is provided with a crank 6 of such 25 length that the lower end thereof will hang below the bottom face of the end sill, as clearly shown in Fig. 3.

7 is a crank formed integral with the inner end of the hand operated lever 5 and 30 positioned at right angles to the crank 6. This crank is more or less deflected, as shown in Fig. 1.

8 is a lever bent to form an integral arm 9, which terminates in an eye 10, said eye being adapted to be slipped over the crank 7 and the bearing rod 5 and in its normal position, it is situated between the crank 7 and one of the bearings 4. The eye is of 40 such diameter that there is no material friction between it and the rod 5. The inner end of the lever 8 has a return bend forming a hook 11. The lever 8 is of such diameter that it is adapted to readily pass through the eye 3 of the standard locking pin. To 45 elevate the locking pin, the rod 5 is revolved by means of the crank 6, whereupon the crank 7 is elevated carrying with it the lever 8, which in turn elevates the locking pin. This construction is such that the draw bar 50 is free to move backward and forward or sideways without damage. In the event of the draw bar dropping by reason of a break in the draft rigging, the crank 6 will be thrown against the end sill, so as to prevent

a complete revolution of the bar 5, whereby 55 the crank 7 is sustained, which results in the locking pin being withdrawn, whereby the car with the damaged coupler will be automatically released from the balance of the train, thus preventing an accident. 60

What I claim is:—

1. A release rigging comprising a hand operated lever, a crank on the inner end of said lever, a pin operating lever loosely journaled on the hand lever, the pin lever 65 having a floating bearing on the crank of the hand lever, whereby the pin lever may be swung bodily on its journal.

2. A release rigging for car couplers comprising a rod mounted on the end sill of the 70 car and provided at one end with a normally horizontal crank and at the other end with a normally vertical handle, a pin lifting lever attached at one end to the locking pin and fulcrumed at its other end on the hand 75 operated rod, the crank of said rod engaging the pin lifting lever between the locking pin and its fulcrum.

3. A release rigging comprising a revolvable hand operated rod having a crank at its 80 inner end, and a pin operating lever having a right angle bend at its outer end terminating in an eye by means of which the pin lever is loosely journaled on said hand lever, the pin lever having a floating bearing on 85 the crank of the hand lever.

4. In a coupler pin controlling device, in combination, a horizontally disposed shaft having a crank arm at its inner end, a lever 90 slidably fulcrumed on the shaft and having a shoulder intermediate of its ends, the free end of the lever being adapted for attachment to a coupler pin, and sliding connection between the crank arm of the shaft and the lever and engaging the lever between its 95 shoulder and its free end.

5. A release rigging comprising a revolvable hand operated rod having a crank at its inner end, and a pin operating lever deflected at its outer end toward said rod and terminating in an eye, by means of which the pin lever is loosely journaled on said hand lever the pin lever having a floating bearing on the crank of the hand lever. 100

6. In an uncoupling device for car-couplers, the combination with a car frame and locking pin, of a revolvable hand operated rod journaled in bearings on the car frame 105

and formed with a handle at its outer end and a laterally extending arm at its inner end, and a pin lifting lever, between its ends extending in the path of said arm, at its inner end releasably engaging said locking pin and provided with means at its outer end for pivotally and slidably engaging said shaft the pin lever having a

floating bearing on the crank of the hand lever.

In testimony whereof I affix my signature in presence of two witnesses.

WALTER P. MURPHY.
